UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A SCARF.

SPECIFICATION forming part of Design No. 12,240, dated April 26, 1881.

Application filed March 10, 1881. Term of patent 3½ years.

To all whom it may concern:

Be it known that I, THOMAS J. FLAGG, a resident of the city, county, and State of New York, have invented a certain new and original Design for Scarfs; and I do hereby declare that the following is a full, clear, and exact description thereof, reference being had to the accompanying drawings, and to the letters of reference marked thereon, making a part of this specification.

My design relates to that class of made-up scarfs for men's wear formed by crossing upon each other two front pieces or aprons depending from an upper supporting-piece placed in the rear thereof.

It consists of a scarf having aprons tapering gradually in width from their lower to their upper ends, and which are crossed upon each other in such manner as that the inner corners of the lower ends of the aprons shall come together, or nearly so, thus making the extreme width of the lower portion of the scarf nearly equal to the combined width of the lower ends of the aprons. The width of the neck-piece constituting the top or upper end of the scarf is about one-fourth that of the lower portion of the scarf, and the upper ends of the aprons are bounded laterally by lines produced from the outer points or angles at the lower end of the scarf to the two outer ends of the top edge or neck-line of the scarf.

In the accompanying drawings, Figure 1 is an elevation of my newly-designed scarf, and Fig. 2 illustrates a modification thereof.

AA represent the crossed aprons of the scarf; b b' b'' b''' b''', their edges, gradually approximating from their lower toward their upper ends. These aprons are so disposed as that the inner corners of their lower ends shall touch, or nearly so, as at c, thus making the extreme distance between the lower outer corners of the scarf, (represented by dotted lines d d,) constituting the extreme width of its lower end, to approximate to the combined width of the lower ends of both aprons. The width of the neck-piece or center piece, E, forming the upper edge

and end of the scarf, upon which its aprons are crossed and from which they depend, is from one-third to one-fourth the width to its lower end. The upper ends of the aprons AA, constituting the upper outer edges, SS, of the scarf, conform laterally with lines d e, drawn from the extreme outer angles of the lower end of the scarf to the extreme outer ends or angles of its upper end or edge, and are defined at the top by lines f e f, drawn from the central intersection, x, of the inner edges of the aprons outwardly at an angle with each other more or less obtuse.

H represents the neckband of the scarf, which forms, however, no part of the design. In the modification shown in Fig. 2 the outer upper edges, SS, of the scarf, formed upon the lines d e, are drawn inward, to present a more or less curved outline, the arc of the curve in each corresponding to the line d e.

It will be observed that this newly-designed scarf embodies in its general outlines a triangle, d e d, having for its base a line, d d, drawn across the widest point of the scarf, and to whose sides d e d e—the outer edges of the upper portion of the scarf conform; and I contemplate making various modifications in the construction of the scarf—such as is suggested, for example, in Fig. 2 of the drawings—without departing substantially from my said design.

What I claim as my design is—

The design for a made-up scarf herein shown and described, the same consisting of the tapering aprons AA, crossed so that their lower inner corners shall closely approximate, and whose upper outer edges, SS, conform to lines drawn from the extreme outer angles, d d, respectively, of the lower end of the scarf to the outer ends of its upper edge.

In testimony whereof I have signed my name to this specification in the presence of two subscribing witnesses.

THOS. J. FLAGG.
